UNITED STATES PATENT OFFICE.

JOSEF SCHIESSLER, OF BADEN, NEAR VIENNA, AUSTRIA-HUNGARY.

APPARATUS FOR RECEIVING AND STRENGTHENING ELECTRIC OSCILLATIONS.

1,165,454.

Specification of Letters Patent.

Patented Dec. 28, 1915.

Original application filed November 23, 1910, Serial No. 593,890. Divided and this application filed December 23, 1912. Serial No. 738,305.

To all whom it may concern:

Be it known that I, Dr. JOSEF SCHIESSLER, subject of the Emperor of Austria-Hungary, residing at Baden, near Vienna, Austria-Hungary, have invented certain new and useful Improvements in Apparatus for Receiving and Strengthening Electrical Oscillations, of which the following is a specification and is a division of my application

10 Serial No. 593,890, filed November 23, 1910. This invention relates to receiving and strengthening apparatus for electrical undulations and has for its object to provide an arrangement, whereby very weak electrical oscillations or undulations such as those occurring in electric telegraphy or telephony with or without wire may be detected and strengthened, so as to cause powerful undulations in the current of the receiving instrument. According to this invention an electrode suspended in a pendulum like manner and easily movable, which is provided with a suitably shaped soft iron core is arranged so as to be fixed in the direction of 20 its axis by an adjustable magnetic field damping its free and forced oscillations. The other electrodes, hereinafter termed contacts, which may be made wholly or in part of a radioactive substance or of an alloy 25 containing the same are adjustably mounted on two oscillatory electrodes which in their turn may be fixed by an adjustable magnetic field.

The resistance formed by the transition of 35 the current between said electrodes, which will hereinafter be referred to as the transitional resistance and which may for instance be an arc, is acted upon by influencing the pendulum electrode by adjustable electromagnets of a suitable magnetic system, which may slide lengthwise with respect to 40 the said electrode in order to obtain a varying sensitivity of the arrangement.

The electromagnets, which may be connected either in series or in parallel, are 45 acted upon by the oscillations or undulations to be detected and strengthened.

The accompanying drawing diagrammatically illustrates a receiving arrangement for 50 telegraphic or telephonic purposes which may also be used as a relay, an alternative method of connecting the receiving telephone being indicated in dotted lines.

The receiver comprises two luminous arcs 55 connected in series and having a self regu-

lating arrangement. One of the metal electrodes σ is common to both arcs. The electrically mounted positive electrode $1'$ of the one luminous arc and the negative electrode $2'$ of the other arc are arranged on opposite sides of the electrode σ which is suspended like a pendulum at 44 by means of a spring blade 43. The two outer electrodes $1'$ and $2'$ are carried by downwardly extending spring blades 45 and 46 which are attached to the connecting terminals 47 and 48 respectively. Corresponding to each of the three electrodes is a holding magnet 49, 50 or 51 and to each of the two outer electrodes $1'$ and $2'$ there is provided in addition to the holding magnet a regulating magnet 52 or 53.

The current for feeding the luminous arc may be derived for example from a lighting circuit conductor, provided with a reducing rheostat, for example an incandescent lamp, or preferably with an accumulator battery connected to the arc circuit at the terminals 11' and 12'. The positive terminal 11' is connected in the arrangement shown through a self induction coil 14' of the kind described to the connecting terminal 47 and the negative terminal 12' is connected to the connecting terminal 48, through the winding of the holding magnet 49 of the central electrode σ and through a self induction coil 25'. The holding magnet 50 and the regulating magnet 52 of one of the luminous arcs ($\sigma, 1'$) are included in a shunt 54 and a second shunt 55 includes the holding magnet 51 and the regulating magnet 53 of the other luminous arc ($\sigma, 2'$).

The luminous arcs are influenced by a magnet system which in the example illustrated consists of two electromagnets 56 and 57 arranged one on each side of the spring blade 43 carrying the central electrode σ . The coils of these electromagnets 56 and 57 are connected in series and included in a conductor 58 which is connected to the terminals 59 and 60.

By means of a switch 61 the terminals 59 and 60 can be included in a conductor 62 connected to the transmitter or, as shown, constituting an air conductor or antenna, 105 which picks up the electric waves transmitted by the transmitter. By moving the switch 61 over onto two other terminals 63 and 64 the air conductor 62 can be connected to a conductor 65 which includes a number 110

of resonance relays 66, 67, 68, 69 in the form of monotelephones or other devices of the usual kind, tuned for various numbers of periods and connected up in series or in 5 parallel. Arranged in connection with each resonance relay is a signaling device 66', 67', 68' or 69', which is set in operation when the corresponding relay responds and which may be optical or acoustical or both.

10 As soon as the waves coming from the transmitter reach the conductor 58 through the air conductor 62 and flow through the electromagnets 56 and 57 these magnets act upon the elastically mounted electrode 6 15 so that the two luminous arcs are varied in the rhythm of or in accordance with the incoming electric waves or the disturbances imposed upon such waves. The electromagnets 56, 57 may be arranged to move along 20 guide bars and may have adjustable cores which act in common by means of an electrode carrying spring as just described upon one electrode, or may each act separately upon one corresponding electrode.

25 The current fluctuations set up in the receiving circuit can be transmitted by means of any suitable method of connection to the telephonic or telegraphic receiver or relay proper. By way of example two different 30 methods of connection are illustrated in the drawing.

In one method of connection the current fluctuations are transmitted by means of the self induction coil 25' and by transformation to the induction coil 72 placed in the 35 circuit 70' of the receiving telephone 71. In the other method of connection, shown by dotted lines, the condenser shown in my co-pending application Serial No. 738304 40 which matured into Patent No. 1,116,130, November 3, 1914, is used. The condenser plates 38, 39 are then connected in parallel, by the conductors 40, 41 to the luminous 45 arcs at the two connecting terminals 47 and 48 thereof, while coil 42, which is adapted to be adjusted on the condenser plates for the purpose of enabling the degree of coupling to be varied, is connected by the conductor 70 with the telephone 71. When 50 using a capacitative-inductive coupling of this kind the condenser is charged by the alternating tension produced in the primary receiving circuit by the fluctuating current. When the condenser is discharged a change 55 again takes place in the electrostatic field, whereby induced currents are produced in the coil 42, which induced currents are employed in the receiving telephone 71.

If the switch 61 be moved onto the terminals 60 63 and 64 for the purpose of receiving a call, the resonance relay conductor 65 will be switched into circuit. Supposing now for example that that relay of a group of relays which is tuned to 500 double vibrations be 65 caused to respond, so much reducing resist-

ance will be switched into the transmitting station system that the vibration generator thereof will produce about 500 periods. Only that resonance relay 66, 67, 68 or 69 which is tuned to 500 double vibrations will 70 then respond and set its corresponding signaling device 66', 67', 68' or 69' in operation. The switch apparatus 61 may be so arranged in a well known way that when the person thus called takes the telephone off 75 the switch hook the receiver circuit is switched in automatically.

The parts may be so arranged that the calling current is only led into the circuit 65 of the resonance relays after it has been 80 strengthened by a telephone relay.

It is obvious that various other arrangements of the magnets and methods of connection may be used without departing from the scope of this invention.

Claims:

1. In an apparatus for receiving and re-laying electrical oscillations, a local circuit comprising a plurality of electric arcs, oscillating electrodes for said arcs, an electro-magnet for each oscillating electrode to control the oscillations thereof, and electro-magnetic means acting upon the arcs in accordance with the oscillations to be reinforced.

2. In an apparatus for receiving and re-laying electrical oscillations, a local circuit comprising a plurality of electric arcs, oscillating electrodes for said arcs, an electro-magnet for each electrode for controlling 100 the oscillations thereof, said electromagnets being supplied with current from said local circuit, and further electro-magnets acting upon some of the electrodes to cause oscillations of the same, the said further electro-magnets being acted upon by the electrical oscillations to be detected and reinforced.

3. In an apparatus for receiving and strengthening electrical oscillations, a local circuit comprising a plurality of electric 110 arcs, oscillating electrodes for said arcs comprising outer electrodes having one arcing point and inner electrodes arranged between the outer electrodes and having two arcing points, an electro-magnet for each outer electrode supplied with current from said local circuit, and further electro-magnets acting upon the inner electrodes, the said further electro-magnets being acted upon by the electrical oscillations to be detected.

4. In an apparatus for receiving and re-laying electrical oscillations, a local circuit comprising a plurality of electric arcs, oscillating electrodes for said arcs comprising outer electrodes having one arcing point and inner electrodes arranged between the outer electrodes and having two arcing points, an electro-magnet for each outer electrode supplied with current from said local circuit, and further electro-magnets acting upon the 125 inner electrodes.

inner electrodes, the said further electro-magnets being acted upon by the electrical oscillations to be detected.

5. In an apparatus for receiving and re-laying electrical oscillations, a local circuit comprising two electric arcs, three oscillating electrodes for said arcs, one of them having two arcing points and being arranged between the two other electrodes having one 10 arcing point each, an electromagnet for each electrode to maintain its position with varying force and supplied with current from said local circuit, a further electromagnet for each of the outer electrodes to 15 regulate their distance from the inner electrode and connected in series with the other electro-magnet allotted to said electrode, and further electro-magnets acting upon the inner electrode, the said further electro-magnets being acted upon by the electrical oscillations to be detected.
6. In an apparatus for receiving and re-laying electrical oscillations, a local circuit comprising two electric arcs between three 25 electrodes mounted on oscillating supports for said arcs, one of them having two arcing points and arranged between the two others having one arcing point each, an electro-magnet included in said local circuit 30 acting upon the inner electrode, an electromagnet for each of the outer electrodes to maintain them in their position with varying force, a second electro-magnet for each outer electrode to adjust the distance between the same and the inner electrode, both 35 electro-magnets allotted to an outer electrode arranged in series in a shunt of the local circuit, further electro-magnets acted upon by the oscillations to be detected, arranged 40 near the oscillating support of the inner

electrode and acting upon the same and a telephone receiver inductively connected with the local circuit.

7. In an apparatus for receiving and re-laying electrical oscillations, a local circuit 45 comprising a plurality of electric arcs, means to ionize the gaps of the arcs by radioactive substances arranged in proximity thereto, oscillating electrodes for said arcs and means acting upon the arcs in accordance with the oscillations to be reinforced.

8. In an apparatus for receiving and re-laying electrical oscillations, a local circuit comprising a plurality of electric arcs, oscillating electrodes for said arcs consisting 55 of alloys containing radioactive metal components, and means acting upon the arcs in accordance with the oscillations to be reinforced.

9. In an apparatus for receiving and re-laying electrical oscillations, a plurality of vibrating electrodes for forming arcs between them in series, a local circuit including said electrodes, and electro-magnetic means to stabilize the vibrations of said electrodes, means controlled by the oscillations to be reinforced to vary in accordance therewith the arcing distance between said electrodes and thereby similarly control the local circuit, and means electrically connected 60 to said local circuit to receive local current varied in accordance with said oscillations.

In testimony whereof I have hereunto set my hand in presence of two subscribing witnesses.
